UNITED STATES PATENT OFFICE.

CHARLES W. COLLINS, OF SEATTLE, WASHINGTON.

CLOTHES-DRYING MACHINE.

1,191,123.

Specification of Letters Patent. Patented July 11, 1916.

Application filed February 13, 1915. Serial No. 7,944.

To all whom it may concern:

Be it known that I, CHARLES W. COLLINS, a citizen of the United States, residing at Seattle, in the county of King and State of Washington, have invented certain new and useful Improvements in Clothes-Drying Machines, of which the following is a specification.

This invention relates to clothes-drying machines; and its object is the improving of such machines to render the same capable of drying clothes more expeditiously and in greater quantities than hitherto with an economical consumption of heat, power and manual labor.

With these and other ends in view, as will appear from the following specification, the invention consists in a plurality of drying compartments which are connected by passageways so as to be operable in series and progressively so that the compartments may be successively rendered inoperative without interfering with the working of the other compartments. In each of said compartments is provided a rotary clothes containing drum which is arranged to be rendered inoperative when the respective compartment is not in use.

The invention further consists in a system of air conduits and controlling valves therefor which are adapted to supply hot air to the various drums for drying purposes and serve in cooperation with the several compartments and passageways to effect an economical drying of the goods.

The invention still further consists in the novel construction, adaptation and combination of parts, as will be hereinafter described and claimed.

In the accompanying drawings, Figure 1 is a horizontal sectional view of a drier embodying the present invention with the valve-operating appliances omitted. Fig. 2 is a transverse vertical section taken substantially through 2—2 of Fig. 1. Fig. 3 is a detail front elevational view of the valve mechanism with a portion of the drier casing in vertical section. Fig. 4 is a sectional view through 4—4 of Fig. 3 with the valves and casing thereabove indicated by broken lines. Fig. 5 is a front elevation of the preferred means for regulating the rotary movements of the cam-shaft to open and close selected valves. Fig. 6 is a fragmentary transverse vertical section to illustrate a different arrangement of the air-intake valves and as-

sociated parts than what is shown in other views.

Referring to Figs. 1 to 5, the numeral 10 designates the ends and 11 the side walls of a casing having partitions 12 and 13 which divide the interior of the casing into four compartments A, B, C and D. The top of the casing, as shown in Fig. 2, is desirably formed of arcuate portions 14. In the outer wall 10 are hinged doors, such as 15 and 15¹, to give access to the different compartments. Within each compartment is a drum comprising end members 16 and peripheral walls 17 of woven wire with an opening in each of the latter and for which are provided hinged doors 18. Extending from each drum-member 16 are axle elements 19 and 19¹ journaled in boxes 20. 21 and 22 represent tight and loose pulleys mounted on the axle elements 19 and for which are provided endless belts 23 extending about pulleys, such as 24, provided on a power-driven shaft 25. Any suitable devices may be provided for shifting the belts from said tight to loose pulleys, or vice versa, or they may be shifted by the hand of the operator, according to which of the drums are to be rotated or caused to be inoperative. Passageways 26, 26¹, 26² and 26³ are provided in said partition to afford communication between the adjacent compartments. Gate valves or doors, as 27, are provided for each of these passageways and may be opened or shut, as by means of levers 28 (Fig. 2) extending outside of the casing and respectively connected with the valves by links 29.

For each compartment are provided ports for the inflow and discharge of air which serves as the drying agent. The air inlet ports are connected by branch pipes 30 with an air supply pipe 30¹ leading from an air-heater. The outlet ports are, in like manner, connected by branch pipes 31 with a discharge pipe 31¹ leading to a power-driven exhaust fan or blower 32. Provided for said inlet ports of the respective compartments are valves 33^a, 33^b, 33^c and 33^d, and for the outlet ports are respectively provided valves 34^a, 34^b, 34^c and 34^d. As shown, the valves are of the puppet type having upright stems 35 passing through guides 36 to below the valve bodies. The intake valves are elevated to open the same by means of bell-crank levers 40^a, 40^b, 40^c, 40^d, which are actuated by cams 41^a, 41^b, 41^c, 41^d mounted on a shaft 42. The levers for the intake valves, as

shown in Figs. 3 and 4, are operable directly by the respective cams; while the levers 43^a, 43^b, 43^c and 43^d for the outlet valves are connected by reach-rods 39 to vibratory arms 44^a, 44^b, 44^c and 44^d which are positioned to be respectively engaged by cams 38^a, 38^b, 38^c and 38^d provided on said cam-shaft to effect the opening of any of the outlet valves. The cams are disposed upon the shaft 42 so that 10 when the latter is suitably turned an inlet valve of a selected compartment and the outlet valve of the compartment in diagonal relations thereto in the casing will be opened. When this occurs, the other valves remain in 15 closed positions. At each end of the shaft is a sprocket wheel 45 (Fig. 5), which are connected by endless chains 46 with sprocket wheels 47 mounted on shafts 48 positioned, as indicated in Fig. 4, at the front and rear 20 of the drier and within convenient reach of the operator when employed at the front or rear.

The shafts 48 are provided with crank-handles 49 with a pointer 49¹ for denoting 25 with respect to a series of numbers or other characters 50 (Fig. 5) the positions of the various cams and the various valves so as to render a predetermined one of the compartments inoperative and the other three 30 compartments operative with respect to the circulation of air, and subject to the regulation of the aforesaid gates.

Where it is desired to create a rapid circulation of air among the compartments, it 35 is advantageous to have all of the valves open in opposition to the direction of travel of the air currents, as otherwise the valves are likely to be opened by suction due to the partial vacuum obtaining within the 40 operating compartments. Under such conditions, the inlet valves instead of opening as illustrated in Figs. 3 and 4, away from the pipe branches through which the air is supplied, should open toward such connections. This modification is clearly shown 45 in Fig. 6. I also show in this view an arrangement of the cams whereby an inlet valve-stem may be actuated thereby without the use of any intermediary bell-cranks 50 or equivalents.

Baffle-plates 51 (Fig. 2) may be used to direct the air to cause it, when traversing a compartment, to pass through a drum instead of around the same.

In operation, the clothes or other articles 55 to be dried, are deposited in the successive drums and are heated through the agency of hot air currents which are admitted through the inlet port of a selected compartment, thence flow through another compartment into a third compartment to be withdrawn therefrom by means of the exhaust fan. For example, assuming that the 60 compartment A for the purpose of replacing 65 in the drum thereof dried articles with

wet goods, is idle, the gates for passages 26 and 26³ which lead into such compartment are closed, and the gates for the passages 26¹ and 26² between the other compartments B, C and D are opened. The inlet valve 33^b for compartment B and outlet valve 34^a of compartment D are now opened by rotating the shaft 42 to cause the respective cams 41^b and 38^d to become effective. When this occurs, the suction created by the fan 32 75 will cause the air to flow as follows: from the supply pipe into compartment B where the air current is deflected by the baffle-plate 51 in this compartment to one side of the drum, thence through the drum and by 80 passage 26¹ to compartment C, through the drum therein through passage 26² and, finally, through drum of compartment D to escape through the port which is uncovered by valve 34^a, as indicated by direction arrows in Figs. 1 and 2. When the drum of 85 compartment A is loaded and that of drum B dried, the gate of passage 26¹ is closed and gate of passage 26³ is opened, whereupon the cam-shaft 42 is turned to open inlet 90 valve 33^c and open outlet valve 34^a resulting in the air entering compartment C and after traversing D escaping from compartment A. The other compartments may in like manner be operated in groups, while 95 the idle one in each cycle is unloaded and loaded to be brought into action in the following cycle. The valves which are not opened by the cams close by their own weight or by the suction of the air when the 100 respective cams are withdrawn. When a drum is to be put into or out of operation, the driving belt 23 therefor is suitably shifted.

The invention is of simple construction, 105 requires little attention, and is peculiarly adapted for laundries doing considerable business and where large quantities of goods must be dried at a small cost.

What I claim as my invention, is—

1. A drier of the character described, having a casing divided into a plurality of compartments and provided with communicative connection therebetween, gates for each such connection, means for individually 115 opening or closing selected of said gates, a rotary drum in each of said compartments, means for rotating the drums, an intake and outlet port for each compartment, means to supply air to the intake ports and withdraw 120 the air from the outlet ports, valves for the respective ports, and means for simultaneously opening the inlet valve of one compartment and the outlet valve for another compartment whereby a flow of air ensues 125 through a number of the compartments.

2. A drier of the character described, having a casing divided into a plurality of compartments and provided with communicative connection therebetween, gates for each 130

such connection, means for individually opening or closing selected of said gates, a rotary drum in each of said compartments, means for rotating the drums, an intake and outlet port for each compartment, means to supply air to the intake ports and withdraw the air from the outlet ports, valves for the respective ports, and means for regulating said valves whereby the course of air through said compartments may be varied.

3. A drier of the character described, divided into compartments, means to afford communication between selected of said compartments, a conduit to supply air for drying into the compartments, a conduit to conduct the air from the compartments, valves for regulating the flow of air to and from said conduits with respect to all of the compartments, and a means operatively connected with all of said valves whereby the air in flowing between the aforesaid conduits is caused to flow through all but one of the compartments, said valve regulating means being adapted in coöperation with the

first-named means to cause each of said compartments to become idle and the other operative in the successive cycles of operation of the drier.

4. A drier of the character described, having a plurality of communicating compartments, doors operable from the outside of the drier for closing the communication between any of said compartments and the adjacent ones, openings for the inlet and discharge of hot air from each of said compartments, valves for the respective openings, and means operatively connected with all of said valves whereby the hot air is supplied to one of said compartments and discharged from another compartment without passing through a selected one of said compartments.

Signed at Seattle, Washington, this 5th day of February, 1915.

CHARLES W. COLLINS.
